UNITED STATES PATENT OFFICE.

SETH H. LEAVENWORTH, OF ROCHESTER, NEW YORK.

METAL SURFACING OR ABRADING MACHINE.

1,413,171.

Specification of Letters Patent. Patented Apr. 18, 1922.

Application filed February 24, 1920. Serial No. 360,657.

To all whom it may concern:

Be it known that I, SETH H. LEAVENWORTH, a citizen of the United States, and resident of Rochester, in the county of Monroe and State of New York, have invented certain new and useful Improvements in Metal Surfacing or Abrading Machines, of which the following is a specification.

The present invention relates to metal surfacing or abrading machines, and it has for an object to provide a machine which will treat metal surfaces in the same manner as the so-called "sand bobbing" process now carried out by skilled workmen who present the metal surface by hand to an abrading element. Another object of the invention is to support the work in cooperative relation to the abrading element in such a manner that the surface may be treated notwithstanding its size or form within, of course, certain limits. Still another object of the invention is to feed a constant and effective supply of abrasive material at the point of engagement between the abrading element and the work piece. A further object of the invention is to prevent the abrading element from operating too long a time on some portions of the work piece and too short a time on other portions of the work piece, as when the work piece has surfaces to be treated situated at different distances from the axis of rotation of such work piece.

To these and other ends the invention consists of certain parts and combinations of parts, all of which will be hereinafter described, the novel features being pointed out in the appended claims.

In the drawings:

Fig. 1 shows in front elevation, a metal surfacing machine constructed in accordance with this invention, the machine being adjusted for operating on deep receptacles or elongated work;

Fig. 2 shows in side elevation, the work supporting mechanism with the abrasive feeding mechanism, the work supporting mechanism being only partially shown;

Fig. 3 is a side elevation of the work supporting mechanism with parts in section, showing the machine provided with the angle attachment permitting the surfacing of flat or shallow work, the angle attachment

being shifted to an abnormal position for facilitating illustration;

Fig. 4 is a fragmentary sectional view of the lower portion of the work supporting frame;

Fig. 5 is a section on the line 5—5, Fig. 3 showing the detaining means for holding the work away from the abrading element;

Fig. 6 is a plan view of the work supporting mechanism showing the machine adjusted for operating on elongated or deep work pieces;

Fig. 7 is a section on the line 7—7, Fig. 6;

Fig. 8 is a detail view showing a bracket which supports the train of gearing in the mechanism which produces the reciprocation of the work and which is adjustable to alter the rotation and the stroke of the work;

Fig. 9 is a detail view of the angle attachment for shallow, flat or substantially flat work;

Fig. 10 is a sectional view through the angle attachment showing the manner in which the latter cooperates with the abrading element or tool;

Fig. 11 is a detail view showing the manner in which deep work pieces are supported in cooperation with the abrading element;

Fig. 12 is a detail sectional view showing the manner in which the direction of rotation of certain parts may be changed to correspond to the work piece;

Fig. 13 is a section on the line 13—13, Fig. 12;

Fig. 14 is a vertical section through the feeding mechanism of the abrasive material;

Fig. 15 is a fragmentary section at right angles to that shown in Fig. 14, the guiding or directing means being shown in elevation; and

Fig. 16 is an enlarged section through another embodiment of the guiding or directing device for the abrasive material.

At the present time in the surfacing or abrading of irregularly shaped bodies of metal preparatory to the plating of such bodies, it is customary to provide a rotating polishing or abrading tool against which the irregularly shaped work is brought by hand, the operative at the same time feeding by hand to the metal surface, the abrasive material, such as powdered pumice stone.

and oil. This method is not only slow, but it requires skilled and highly paid workmen of long experience, thus making the cost of surfacing, or as it is called "sand bobbing" the body, a very expensive operation.

According to this invention, a machine has been provided which may be operated by unskilled workmen, provision being made whereby relative movement between the abrading element and the work piece is obtained in a manner to correspond to the shape and size of the work piece, while at the same time, the abrasive material is fed at the point of contact between the abrading element and the work piece.

Referring to the embodiment of the invention herein illustrated, 1 indicates the abrading or polishing element which may be of a form most desirable for the work operated upon. In this embodiment, this abrading element is a disk shaped rotary member formed of fabric or other suitable yielding material and mounted upon a shaft 2 supported in bearings upon a frame 3, the shaft having an idler 4 and a fixed pulley 5 thereon for engagement by a belt 6, which may be shifted from one pulley to the other through the shifter 7.

30 The abrasive material, such as pumice stone, may be contained in a hopper 8 supported above the abrading element 1 preferably by a frame 9 suspended from the ceiling of the building in which the apparatus is arranged. The flow through the discharge opening 10 of this hopper may be controlled by a rotary pocketed or bladed member 11 which has a shaft 12 extended to one side of the discharge opening 10 with

40 a pulley 13 loosely mounted thereon and adapted to be connected to and disconnected from the shaft by a sliding clutch collar 14. This pulley may be driven in any suitable manner. In this instance, it connects by a

45 belt 15 with a pulley 16 on the end of a vertical shaft 17 which in turn is driven in any suitable manner. In order to agitate the material within the hopper 8, an agitator is provided preferably in the form

50 of a vertical shaft 18 having scraper arms 19 and driven preferably through a sprocket 20 on said shaft 18, said sprocket through a chain 21 connecting with a sprocket 22 on the shaft 17. In order to guide and di-

55 rect the abrasive material from the discharge opening 10 to the abrading element 1, a guiding and directing device is employed preferably in the form of an open ended chute or receptacle 23 which is disposed directly

60 beneath the discharge opening 10 and is preferably adjustably supported through an arm 24 extending rearwardly from the receptacle and adjustable in a clamp 25 which in turn is adjustably mounted on a rod 26 depending from the frame 9 in rear of the

hopper 8. The guiding and directing chute 23 is preferably in the form of an open ended box having inside thereof, two deflecting plates 27 adjustably mounted in the front and rear walls of the receptacle 23 on a bolt 28 so that they may be made to converge toward the abrading element 1 as shown in Fig. 15 in dotted lines. An apron 29 may be secured to the receptacle 23 and is preferably in the form of an angle plate 75 adjustably secured to the front wall by a fastening device 30 operating in a slot 31 in the apron. This apron is provided in order that the material dropping on the abrading element 1 will be carried by the latter downwardly through the point of engagement between the abrading element and the work piece. In Fig. 16, a modification of the guiding and directing chute is illustrated. In this modification, the receptacle 23^a has its side walls provided with depending flanges 23^b one of the side walls indicated at 23^c being adjustable so that the flanges, which are projected downwardly on opposite sides of the abrading element, 90 may be made to correspond to the thickness of the abrading element. Adjustment of the wall 23^c may be provided by providing the latter with flanges 23^d and connecting fastening devices 23^e to said flanges, said 95 fastening devices operating in slots 23^f in the front and rear walls of the receptacle 23^a. Instead of two deflectors, the receptacle is provided with three deflectors 27^a in order to break up the abrasive material 100 as well as to direct the same to and uniformly over the abrading element whatever the position of the latter may be.

The machine has been shown as adapted for working upon two types of work pieces, 105 one indicated at 32 being of elongated construction and the other indicated at 33 being of flat or shallow construction. When used for operating on deep or elongated work pieces, a head 34 is employed of a shape 110 preferably to fit within the elongated work piece 32, said head preferably having at intervals, pieces 35 of yielding or friction producing material which will engage the interior wall of the hollow work piece 32 115 for sustaining the work piece upon the head. The head is rotated in a manner to cause the work piece to be rotated in contact with the abrading element 1, being in this instance, secured by a set screw 36 to a shaft 120 37 which turns in a frame or arm 38.

When used for abrading or polishing flat or shallow objects 33, the latter is held against a head 133 by suitable holding means such as a screw 133^a and the head is rotated 125 preferably about two parallel axes out of alignment with each other for the purpose of crossing the cuts made by the abrasive material and destroying the tendency of the abrading element to cut spiral lines on 130

the work piece. It also enables the abrading element to cut across the center of the work piece without having a high point of slowest surface speed at a fixed axis of center. This result may be secured by forming the head with a sleeve 134 detachably secured by a set screw 135 to a sleeve 136 in which a crank pin 137 is mounted to turn. The sleeve 136 has a pinion 138 at its inner end which meshes with an internal gear 139 on a non-rotating part 140 in which a shaft 141 turns, said shaft 141 carrying the crank or wrist pin 137 eccentrically thereto so that when the shaft 141 is rotated, the wrist pin 137 will be caused to revolve and carry the head 133 with the work piece 33 in a circle while at the same time the work piece 33 will be caused to rotate about an axis concentric therewith through the meshing 20 of the gear 138 with the internal gear 139. The shaft 141 is mounted in a frame 142 to which the part 140 is detachably secured at 143 so that direct drive may be obtained by fastening the sleeve 134 to the shaft 141. The frame 142 is pivotally connected by a pin 144 with a bracket 145 formed in two parts and detachably secured by bolts 146 to a frame 38, thus permitting the frame 142 to swing at an angle to the frame 38. To the end that a stub shaft 141 may be driven from the shaft 37, a bevel gear 147 is detachably secured to the shaft 37 to mesh with a bevel gear 148 which turns on the pin 144, and in turn meshes with a bevel gear 149 on the shaft 141. The shaft 37 is supported and moved so that work pieces of various sizes and shapes may be treated upon the machine. In this embodiment the frame 38 is mounted to turn about an upright axis on another frame 39, the frame 38 being held in an adjusted position on said frame 39 by bolts 40 carried by the frame 39 and operating in arcuate slots 41 concentric with the axis of turning of the frame 38. The frame 39 is preferably mounted to reciprocate on a frame 42 provided with horizontal guides, the frame 42 carrying a shaft 43 parallel with the line of movement of the frame 39 for transmitting motion to the shaft 37 on the frame 38. In this instance, this motion is transmitted through a bevel gear 44 on the shaft 37 meshing with a bevel gear 45 on a stub shaft 46 which turns in the bearing 47 forming the pivotal connection between the frames 38 and 39. The stub shaft 46 also carries a bevel gear 48 which is adapted to mesh with either one of two pinions 49 or 50 arranged on the shaft 43 to turn with said shaft but to move axially thereof. In this instance, these two pinions are connected together by a sliding frame 51 mounted in a housing formed by the frame 39 and being supported for sliding movement by headed bolts 52 which operate in slots 53 formed in the cover 54 of the housing. This cover 54 also has a bracket 55 on the exterior of the housing on which a lever 56 is pivoted at 57, said lever being extended into engagement with the slide 51 and having its opposite end adapted to be secured by a bolt 58 in either one of two openings 59. When secured in one of said openings, the gear 49 will lie in mesh with the gear 48 whereas, when secured in the other opening, the gear 50 will lie in mesh with the gear 48 and this meshing will be maintained notwithstanding the reciprocation of the frame 39 on the frame 42. The purpose of this change is to permit the work piece to be rotated in one and the same direction notwithstanding the use of the angle attachment for flat work which, if this change gear were not provided, would give the work piece a movement in the opposite direction.

The shaft 43 may be driven in any suitable manner as for instance by a bevel gear 60 which in turn meshes with a bevel gear 61 on the shaft 62 at the inner end of the frame arm 42. The shaft 62 also carries a bevel gear 63 meshing with a bevel gear 64 on a vertical shaft 65 journalled on the frame arm 42 and driven in any suitable manner but preferably having a universal joint 65^a therein to permit the bodily movement of the work piece.

Mechanism is provided for imparting a reciprocatory motion to the frame or carriage 39 and this reciprocatory motion is so controlled that it will cause the movement of the motion of the reciprocating frame 39 to dwell longer at those points where the abrading element is operating on the work piece farthest from the axis of rotation of the work piece and shorter at those points where the abrading element is working on the work piece nearest the center of rotation of the work piece, the purpose of this being to prevent any portion of the work piece being surfaced or abraded greater than another portion for it will be apparent that if the work piece is held in engagement with the abrading element, the same length of time nearest its center of rotation as it is farthest removed from the center, then the portion nearest the center will receive more polishing than the portion farthest removed from the center. A desirable form for this reciprocating mechanism comprises a gear wheel 66 mounted on the shaft 62 which meshes with a pinion 67 in turn meshing with a pinion 68. The pinion 67 is supported on a shaft 69 which is adjustable in a slot 70 formed in a bracket 71 which is detachably secured to the frame 42 by bolts 72. The slot 70 in the bracket 71 is concentric with the bearing opening 73 of the gear 68 and provides for the substitution of a larger gear 130

66 on the shaft 62 so that a variation in the speed of the gear 68 may be obtained, and thus a change in the ratio of movement between the rotation of the work piece and the reciprocation or bodily movement of the work piece is secured. The gear 68 has secured to its outer face a guide piece 74 which extends diagonally of the gear, projecting from both sides of the latter and having a crank pin 75 adjustable therein to different positions so that said crank pin may be situated at different distances from the center of rotation of the gear 68 in order to cooperate with different portions of a curved or irregularly formed way in a swinging member 76 detachably pivoted at 77 to the frame 42. The curved way 78 is formed in such a manner that a movement may be imparted to the swinging member through the crank pin 75 which will correspond to the desired bodily movement of the work piece so that the abrading element will operate on the work piece an amount substantially equal to the distance the field of operation is situated from the axis of rotation of the work piece. The swinging member 76 is removable so that a swinging member having another form of way may be used when the one herein shown does not provide the proper movement. The connection between the swinging member 76 and the reciprocating carriage 39 may be established through a pitman 80 which is pivoted at 81 to a block 82 adjustable on a way 83 formed on one side of the swinging member 76, the swinging member having also a similar way 83 on the opposite side so that by reversing the swinging member a movement in the opposite direction is provided which will give still further adjustments. The pitman 80 has a resilient portion 84 and is pivotally connected at 85 with the reciprocating carriage 39, the resilient portion being provided to prevent any undue strain between the work piece and the abrading element.

The frame 42 is preferably mounted to swing about an upright axis and it is also preferably vertically adjustable. This result is secured in this instance, by providing a screw 86 on a frame 87 and mounting said screw to turn in bearings 88 at its upper and lower ends. Two nuts 89 are provided on the screw and between these nuts the frame 42 is secured, the adjustment of the nuts on the screw effecting the vertical adjustment of the swinging frame 42 and the turning of the screw in its bearing providing for the swinging of the frame about an upright axis. The frame 42 is vertically adjustable in order that the axis of the work piece may be substantially arranged in a horizontal plane with the axis of rotation of the rotary abrading element and the

swinging of the frame about a vertical axis 65 is provided in order that the work may be yieldingly held toward the abrading element so that the work may swing toward and from the abrading element to accommodate machines to different portions of the work piece. The yielding in this instance, is preferably secured by providing a counter-weight 90 which is suspended by a flexible cable 91 passing about a pulley 92 at the top of the frame 87 and connecting 75 with an arm 93 on the screw 86. For the purpose of holding the work piece away from the abrading element, a detent 94 may be provided pivoted at 95 and held under the action of a spring 96 into cooperation 80 with the periphery of a disk 97 which permits the ordinary swinging of the frame 42, but when the frame is swung to a certain position, a shoulder or abutment 98 on this disk will be engaged by the detent 94 85 and hold the work piece away from the abrading element.

The frame 87 may be mounted to swing about a horizontal axis and also to move horizontally in two directions at right angles to each other. The first of these results is for the purpose of causing the work piece to be presented to the abrading element at an angle so that lines left on the work piece by previous operations such as spinning will be obliterated, preferably obtained by pivoting the frame at 99 on a shaft which is supported by two brackets 100, adjusting devices in the form of bolts 101 and slots 102 in one of the brackets securing 100 the frame 87 in its adjusted position about its axis 99. The brackets 100 are preferably formed on a carriage 103 which is guided on ways 104 on another carriage 105, the latter moving on ways 106 formed on a base 107. 105 Adjusting screws 108 and 109 may be provided respectively for moving the carriage 103 on the carriage 105 and the carriage 105 on the base 107.

A metal surfacing machine constructed in accordance with this invention makes it possible to dispense with skilled labor for surfacing metal ware goods. It performs the work similar to the usual sand bobbing process. The abrasive material or substance 115 is fed at the point of contact between the work piece and the abrading element, these two parts being subjected to rotation in the same direction at their point of contact but at different speeds. In addition, the work piece is given a bodily movement which corresponds to the form, shape and size of the work piece. Provision is made whereby the abrading element whether near to or far from the axis of rotation of the work 125 piece, has sufficient time to properly surface such work piece. The mechanism as a whole is simple in operation and is provided

with adjustments which permit articles of various forms, shapes and sizes to be worked upon.

What I claim as my invention and desire

5 to secure by Letters Patent is:

1. A metal surfacing machine comprising an abrading element rotatable about a horizontal axis, means for supporting a work piece for rotary engagement with that portion of the abrading element moving downwardly, a chute for delivering an abrasive substance to the rotary abrading element above the axis of said element, and an apron arranged between said chute and 10 the point of engagement of the rotary abrading element with the work piece for the purpose of causing the abrading element, through centrifugal force to carry the abrasive substance to the point of contact between the abrading element and the work piece.
- 15 2. A metal surfacing machine comprising an abrading element rotatable about a horizontal axis, mechanism for supporting the work piece for cooperation with that portion of the rotary abrading element which turns downwardly, and mechanism for delivering an abrasive substance to the point of contact between the abrading element and the work piece comprising a hopper, a chute arranged above the abrading element and below the hopper to direct the abrasive substance on the abrading element, means 20 permitting the adjustment of the chute relatively to the hopper and the abrading element to accommodate abrading elements of different sizes, and mechanism for feeding the abrasive substance from the hopper to the chute.
- 25 3. A metal surfacing machine comprising an abrading element rotatable about a horizontal axis, mechanism for supporting the work piece for cooperation with that portion of the rotary abrading element which turns downwardly, and mechanism for delivering an abrasive substance at the point of contact between the abrading element and the work piece comprising a chute arranged to deliver material on the abrading element, a hopper, and a rotary measuring feeding device for feeding the abrasive substance from the hopper to the chute in measured 30 quantities.
- 35 4. A metal surfacing machine comprising an abrading element rotatable about a horizontal axis, mechanism for supporting the work piece for cooperation with that portion of the rotary abrading element which turns downwardly, and mechanism for delivering an abrasive substance at the point of contact between the abrading element and the work piece comprising a chute arranged to deliver the abrasive substance to the abrading element above the axis of the latter, a

hopper, a rotary feeding device for feeding the abrasive substance from the hopper to the chute, an agitator in the hopper, and a common driving mechanism for the agitator and the rotary feeding device.

5. A metal surfacing machine comprising an abrading element rotatable about a horizontal axis, mechanism for supporting the work piece for cooperation with that portion of the rotary abrading element which turns downwardly, and mechanism for delivering an abrasive substance at the point of contact between the abrading element and the work piece comprising a chute arranged to deliver the abrasive substance to the abrading element above the axis of the latter, a hopper, a feeding device for feeding the material from the hopper to the chute, and mechanism for operating said rotary feeding device having manually controllable means therein for stopping and starting the feeding device.

6. A metal surfacing machine comprising an abrading element rotatable about a horizontal axis, mechanism for supporting the work piece for cooperation with that portion of the rotary abrading element which turns downwardly, and mechanism for delivering an abrasive substance at the point of contact between the abrading element and the work piece comprising a chute having adjustable deflectors therein for adapting said chute to abrading elements of different thicknesses.

7. A metal surfacing machine comprising an abrading element rotated about a horizontal axis, mechanism for supporting the work piece for cooperation with that portion of the rotary abrading element which turns downwardly, and mechanism for delivering an abrasive substance at the point of contact between the abrading element and the work piece comprising a chute having side walls projecting downwardly on opposite sides of the abrading element.

8. A metal surfacing machine comprising an abrading element rotated about a horizontal axis, mechanism for supporting the work piece for cooperation with that portion of the rotary abrading element which turns downwardly, and mechanism for delivering an abrasive substance at the point of contact between the abrading element and the work piece comprising a chute having side walls projecting downwardly on opposite sides of the abrading element, said side walls having relative adjustment to vary the distance between them.

9. A metal surfacing machine comprising an abrading element rotatable about a horizontal axis, mechanism for supporting the work piece for cooperation with that portion of the rotary abrading element which turns downwardly, and mechanism for de-

livering an abrasive substance at the point of contact between the abrading element and the work piece comprising a chute having side walls projected downwardly on opposite sides of the abrading element, and an apron arranged between the chute and the point of contact between the abrading element and the work piece.

10. A metal surfacing machine comprising an abrading element rotatable about a horizontal axis, mechanism for supporting the work piece for cooperation with that

portion of the rotary abrading element which turns downwardly, and mechanism for delivering an abrasive substance at the point of contact between the abrading element and the work piece comprising a chute having side walls projected downwardly on opposite sides of the abrading element, and an apron arranged between the chute and the point of contact between the abrading element and the work piece, said apron being adjustably supported by the chute.

SETH H. LEAVENWORTH.

Certificate of Correction.

It is hereby certified that in Letters Patent No. 1,413,171, granted April 18, 1922, upon the application of Seth H. Leavenworth, of Rochester, New York, for an improvement in "Metal Surfacing or Abrading Machines," an error appears in the printed specification requiring correction as follows: At the end of the specification insert the following reservation:

No claim is herein made to the construction of the work holder, and the adjustment and means for reciprocating the turning the work, as the subject matter thereof forms the basis of an application filed by me on November 13, 1920, Serial No. 423,970.; and that said Letters Patent should be read with this correction therein that the same may conform to the record of the case in the Patent Office.

Signed and sealed this 16th day of May, A. D., 1922.

[SEAL.]

KARL FENNING,
Acting Commissioner of Patents.
